UNITED STATES PATENT OFFICE.

FRANZ TRINKS, OF BRUNSWICK, GERMANY.

CALCULATING-MACHINE.

1,118,830.

Specification of Letters Patent.

Patented Nov. 24, 1914.

Application filed March 16, 1914. Serial No. 825,069.

To all whom it may concern:

Be it known that I, FRANZ TRINKS, manufacturer, citizen of the Duchy of Brunswick, Empire of Germany, residing at Brunswick, Germany, have invented certain new and useful Improvements in Calculating-Machines, of which the following is a specification:

My invention relates to improvements in calculating machines, and more particularly in calculating machines in which a setting mechanism is provided which consists of setting disks provided with radially shiftable teeth representing the values to be set on the disks and cam disks for shifting in each setting disk the desired number of teeth into operative positions, and in which furthermore mechanism is provided for counting the number of revolutions of a crank arranged for operating the setting disks and transmitting the values set thereon to the numeral wheels of a registering mechanism. In machines of this class the registering mechanism is mounted on a carriage which is slidable in a direction parallel to the axis of the setting mechanism, so that the numeral wheels of the registering mechanism can be thrown into coöperation with setting disks of different orders. At the left of the registering mechanism, and ordinarily co-axially therewith the numeral wheels of the revolutions counting mechanism are mounted which coöperate with a single tooth wheel connected with the crank and adapted to advance or return one of the numeral wheels during each rotation of the crank. A machine of this construction is shown for example in my prior Patent Nr. 979358, dated December 20, 1910. If in this machine the carriage is shifted in order to bring the setting disks into position for coöperation with numeral wheels of higher order, also the single tooth wheel is shifted into position for coöperation with a numeral wheel of higher order, because the single tooth wheel and the coöperating revolutions counting mechanism are shifted relatively to each other by shifting the carriage.

When performing divisions on the calculating machine, and the numbers are large, it is not possible to use all the orders of the numeral wheels for indicating the quotient and particularly the decimals of the same. For example, if the calculating machine is provided with seven setting disks, ten nu-

meral wheels in the registering mechanism, and eight numeral wheels in the revolutions counting mechanism, and if it is desired to perform on the machine the following division:

60

3122111:711111,

and to obtain several decimals, the division is at first performed in the usual way:

65

3122111000:711111,

whereupon the revolutions counting mechanism shows the quotient 4.390, and the registering mechanism displays the remainder: 333710. If it is desired to continue the division so as to obtain further decimals, the said remainder must be transferred to the left hand peep holes of the registering mechanism before the calculation is continued. The quotient 4390 must be removed from the revolutions counting mechanism and separately noted for taking down the final result, because the quotient which is obtained by the following step of the calculation appears on the same numeral wheels of the revolutions counting mechanism, so that the new quotient would be added if the first one were not erased, while they must be placed one beside the other. This addition would of course give a wrong result.

80

85

The object of the improvements is to provide a calculating machine in which it is not necessary to separately write down the quotients of the first calculation, and by which wrong results are safely avoided.

90

With this object in view my invention consists in so mounting the driving member for the revolutions counting mechanism or the single tooth wheel, that it can be shifted into position for coöperation with any one of the numeral wheels of the revolutions counting mechanism without shifting the carriage on which the registering and revolutions counting mechanisms are mounted. Therefore the operating member can be shifted for example in such a way, that it acts on the last numeral wheel at the left even if the carriage is in its extreme left hand position.

95

100

For the purpose of explaining the invention an example embodying the same has been shown in the accompanying drawings, in which the same letters of reference have been used in all the views to indicate corresponding parts.

105

110

In said drawings—Figure 1, is a front view of a calculating machine with the cover of the casing partly removed, Fig. 2, is a cross-section taken on the line 2—2 of Fig. 1, 5 Fig. 3, is a cross-section taken on the line 3—3 of Fig. 1, and Fig. 4, is an enlarged detail view showing the shiftable single tooth wheel of the revolutions counting mechanism.

10 Referring to the example illustrated in the drawings, the setting mechanism consists of setting disks *a* which are mounted on a main shaft *d*, and which are equipped with nine radially shiftable teeth *a*¹. For 15 shifting the said teeth cam disks *a*² are provided which are provided with hand pieces *a*³ projecting through slots *a*⁴ of the cover *a*⁵ of the machine casing. The shaft *d* and the setting disks mounted thereon are adapt- 20 ed to be rotated by means of a crank *d*⁸ through the intermediary of gear wheels *d*¹ and *d*². When the setting disks *a* are thus rotated those of the teeth *a*¹ which have been 25 shifted into operative positions engage in the teeth of intermediate gear wheels *b*² which are in mesh with teeth *b*¹ of numeral 30 wheels of the registering mechanism *b*. The registering mechanism and the intermediate gear wheels *b*² are mounted on a carriage *y* which is adapted to be shifted in a direction 35 parallel to the shaft *d* of the setting mechanism and which is mounted on the bottom plate *x* of the machine. At the left of the registering mechanism *b* a revolutions 40 counting mechanism *c* is mounted on the carriage *y*, and the numeral wheels of the revolutions counting mechanism are each provided with gear teeth *c*¹. The said gear teeth are in mesh with intermediate gear 45 wheels *c*² which are loosely mounted on a common shaft *w*. For resetting the registering mechanism *b* and the revolutions counting mechanism *c* wing nuts *b*³ and *c*³ are provided which are located at opposite 50 sides of the carriage *y*.

The revolutions counting mechanism is adapted to be operated by means of a single tooth *j* which is mounted on the machine frame *v* and which is adapted to be rotated 55 from the shaft *d* of the setting disks through the intermediary of gear wheels *e* and *f*. In my improved machine the said single tooth is shiftable mounted in such a way, that it can be thrown into coöperation with 60 any one of the intermediate gear wheels *c*² without shifting the carriage *y*. In the example shown in the drawings the gear wheel *f* is connected to a subsidiary shaft *g* which is mounted parallel to the shaft *w* of the intermediate gear wheels, and which is provided 65 with notches *h* corresponding to the number and relative distance of the numeral wheels of the revolutions counting mechanism. On the said shaft a sleeve *k* is shiftable mounted which carries the single tooth

j. The single tooth can be set on the shaft *g* in the positions corresponding to the numeral wheels of the revolutions counting mechanism by means of a locking lever *m* which is acted upon by a spring *l* and is 70 adapted to be operated by the hand of the operator. At one of its ends the said locking lever projects beyond the circumference of the sleeve *k* and at its opposite end it is provided with a tooth *n* which is adapted 75 to engage in the notches *h*. When depressing the locking lever *m* the sleeve *k* and the single tooth *j* are disconnected from the shaft *g*, by the withdrawal of tooth *n* from notch *h*, whereupon the sleeve can be 80 shifted and afterward fixed in the new position. In order that the single tooth may more easily be disconnected from the shaft a slide *z* may be provided which is slidable within a slot *c*⁵ made in the cover *c*⁴ of the 85 machine casing and parallel to the subsidiary shaft *g*. The slide is provided with a tongue *z*¹ which engages in an annular groove in the sleeve *k*, and is also provided with a spring actuated pin *z*² for releasing 90 the locking lever *m*.

In order that it be impossible to turn the driving member or single tooth *j* into a position in which the said tooth cannot co-operate with any of the numeral wheels of 95 the revolutions counting mechanism *c* locking means may be provided which permit rotation of the single tooth only when it is in the correct position with relation to one of the numeral wheels. As shown such 100 locking means consist of two notched bars *o* which are preferably located immediately at the front and rear of the single tooth when in normal or inoperative position, in order that when rotating the machine crank 105 in either direction always one of the bars *o* is operative. If upon rotation of the machine crank the single tooth is in correct position it passes through the notches *q* of the bars, and if it is not in correct position rotation is prevented by the teeth *p* of the bar *o*. 110

When transmitting the remainder of the first step of the calculation to the left hand numeral wheels of the registering mechanism, that is in the example referred to above the number 333,710, an additional rotation of the machine crank is necessary. In order that this operation of the machine crank may not result in a wrong registration in the revolutions counting mechanism, means are provided for temporarily throwing the single tooth entirely out of operation. This may be done in various ways. To show what may be done the shaft *g* is 115 provided near its left hand end with a notch *h*¹ and the sleeve *k* is adapted to be shifted with the single tooth *j* beyond the last one of the numeral wheels of the revolutions counting mechanism and into position in 120 125 130

which the single tooth j is out of engagement with any of the numeral wheels and in register with the notch h^1 .

While in describing the mechanism reference has been made to a simple embodiment thereof, I wish it to be understood that my invention is not limited to the construction shown in the drawings. Other means will readily suggest themselves to those skilled 10 in the art. For example the single tooth may be so mounted as to be shiftable on its sleeve, in which case it is shifted out of operative position without shifting the sleeve.

15 I claim herein as my invention:

1. In a calculating machine the combination with the setting mechanism, the registering mechanism, and the revolutions counting mechanism, said revolutions counting 20 mechanism comprising a plurality of numeral wheels, and said setting mechanism and said registering and revolutions counting mechanisms being shiftable relatively to each other, of an operating member for the revolutions counting mechanism adapted to be shifted independently of the registering mechanism into position for coöperation with any one of the numeral wheels of the revolutions counting mechanism.

2. In a calculating machine the combination with the setting mechanism, the registering mechanism, and the revolutions counting mechanism, said revolutions counting mechanism comprising a plurality of 25 numeral wheels, and said setting mechanism and said registering and revolutions counting mechanisms being shiftable relatively to each other, of an operating member for the revolutions counting mechanism adapted to be shifted independently of the registering mechanism into position for coöperation with any one of the numeral wheels of the revolutions counting mechanism, and means 30 inoperative when the operating member is 40 in position for coöperation with one of the numeral wheels to lock the operating member.

3. In a calculating machine the combination with the setting mechanism, the registering mechanism, and the revolutions counting mechanism, said revolutions counting mechanism comprising a plurality of 35 numeral wheels, and said setting mechanism and said registering and revolutions counting mechanisms being shiftable relatively to each other, of an operating member for the revolutions counting mechanism adapted to 45

be shifted independently of the registering mechanism into position for coöperation with any one of the numeral wheels of the revolutions counting mechanism, and at least one bar located in position for locking the operating member against operation and provided with notches for permitting the passage of the operating member when in 60 proper position with relation to the numeral wheels of the revolutions counting mechanism.

4. In a calculating machine the combination with the setting mechanism, the registering mechanism, and the revolutions counting mechanism comprising a plurality of numeral wheels, and said setting mechanism and said registering and revolutions counting mechanisms being shiftable relatively to each other, of an operating member for the revolutions counting mechanism adapted to be shifted independently of the registering mechanism into position for coöperation with any one of the numeral 70 wheels of the revolutions counting mechanism, and at least one bar located in position for locking the operating member against operation and provided with notches for permitting the passage of the operating member when in proper position with relation to the numeral wheels of the revolutions counting mechanism and with a notch 75 permitting the passage of the operating member when out of position for coöperation with the numeral wheels.

5. In a calculating machine the combination with the setting mechanism, the registering mechanism, and the revolutions counting mechanism comprising a plurality of 80 numeral wheels, and said setting mechanism and said registering and revolutions counting mechanisms being shiftable relatively to each other, of an operating member for the revolutions counting mechanism adapted to be shifted independently of the registering mechanism into position for coöperation with any one of the numeral wheels of the revolutions counting mechanism, and means 85 to temporarily render said operating member inoperative.

In testimony whereof I have hereunto set my hand in presence of two subscribing witnesses.

FRANZ TRINKS.
